(57) **CLAIM**

The ornamental design for a smart lock as shown and described.

DESCRIPTION

FIG. 1 is a front view of a first unit of a smart lock, wherein a screen of the smart lock is on;

FIG. 2 is a front view of the first unit of the smart lock of FIG. 1 thereof, wherein the screen of the smart lock is off; FIG. 3 is a left side view of the first unit of the smart lock of FIG. 1 thereof;

FIG. 4 is a right side view of the first unit of the smart lock of FIG. 1 thereof;

FIG. 5 is a top view of the first unit of the smart lock of FIG. 1 thereof;

FIG. 6 is a bottom view of the first unit of the smart lock of FIG. 1 thereof;

FIG. 7 is a rear view of the first unit of the smart lock of FIG. 1 thereof;

FIG. 8 is a perspective view of the first unit of the smart lock of FIG. 1 thereof, wherein the screen of the smart lock is on; FIG. 9 is another perspective view of the first unit of the smart lock of FIG. 1 thereof, wherein the screen of the smart lock is on;

FIG. 10 is a front view of a second unit of the smart lock; FIG. 11 is a left side view of the second unit of the smart lock of FIG. 10 thereof;

FIG. 12 is a right side view of the second unit of the smart lock of FIG. 10 thereof;

FIG. 13 is a top view of the second unit of the smart lock of FIG. 10 thereof;

FIG. 14 is a bottom view of the second unit of the smart lock of FIG. 10 thereof;

FIG. 15 is a rear view of the second unit of the smart lock of FIG. 10 thereof;

FIG. 16 is a perspective view of the second unit of the smart lock of FIG. 10 thereof;

FIG. 17 is another perspective view of the second unit of the smart lock of FIG. 10 thereof;

FIG. 18 is a side view of the smart lock wherein the first unit and the second unit of the smart lock are set up on a door; FIG. 19 is a perspective view of the first unit of the smart lock of FIG. 1 thereof, wherein the first unit of the smart lock is set up on a door, wherein the screen of the smart lock is on; and,

FIG. 20 is a perspective view of the second unit of the smart lock of FIG. 10 thereof, wherein the second unit of the smart lock is set up on the door.

(Continued)

The broken lines in the drawings form no part of the claimed design.
